DISAPPEARING SUPPORT FOR BUSINESS
MACHINES AND THE LIKE

Carl Brynolf Lundstrom, Little Falls, N. Y.

Application October 22, 1942, Serial No. 462,974

4 Claims. (Cl. 312—27)

This invention relates to cabinets of the so-called disappearing instrument type, and is directed particularly to a typewriter desk having a horizontal typewriter supporting platform which moves between a projecting working position and a lower retracted storing position in which the platform is wholly within the pedestal of the desk. In its motion between these two limiting positions, the platform is horizontal at all times.

Mechanisms of this general description have been known, but the linkage used has been such as to require considerable metal for the levers and for certain counterbalancing springs. The present invention produces a structure which can be built almost completely of wood, which requires no counterbalancing and which is rigid when in the projecting position.

Success in this respect is secured by the use of two sets of parallel wooden suspender links for sustaining and guiding the platform. The links of each pair have their pivots slightly offset vertically and swing in a common plane so that they engage one another as the platform reaches its projecting position and then form what is in effect a rigid extension of the platform serving to resist any tilting motion of the platform.

The platform is chiefly supported in its projecting position by a latching bar which underlies the platform, forward of the point of interengagement of the links, and near the forward edge of the desk.

The preferred embodiment of the invention is illustrated in the accompanying drawings in which:

Fig. 1 is a vertical section through the pedestal of a desk showing the platform in its retracted position.

Fig. 2 is a similar view showing the platform in its projecting position.

Fig. 3 is a fragmentary perspective view showing the parts in the position of Fig. 2 and illustrating the interengagement of the links and the engagement of the latching bar.

Fig. 4 is a fragmentary perspective view showing the platform in its retracted position. The view is taken looking upward and to the left.

Fig. 5 is a face view of the bottom of the platform showing in full lines the engaged position of the latching mechanisms and in dotted lines the releasing positions thereof.

Only one pedestal portion of the desk is illustrated in the drawings, and this is indicated as having legs 7, sides 8 and 9, and a back 11. The

front of the pedestal is open except for a hinged door 12. In Fig. 2, the door 12 is shown swung back to clear the platform. The top or bed of the desk is indicated at 13. The parts so far described are conventional and may take any form known in the art.

In effect, the desk pedestal forms a cabinet open at its front. Mounted within the pedestal are supporting members 14 which extend from front to back of the interior of the cabinet near the top thereof and against the side walls 8 and 9. In the forward corners there are vertical struts 15, whose upper ends are spaced from the supports 14 so that the latching bar, hereinafter described, may enter above the upper ends of the struts 15. The lower edges of the supports 14 are cut away to permit this, as is indicated at 16. Extending across the inner face of the back 11 is a retaining strip 17. This strip serves as a reinforcement and as a keeper for a second latch.

The machine platform 18 is horizontal and is sustained by a pair of forward links 19 and a pair of rear links 21. The forward links are pivoted at 22 to the support 14 and at 23 to the platform 18. The rear links are pivoted at 24 to the support 14 and at 25 to the machine platform. The hinge connections can be made by means of wood-screws, and if preferred, these may turn in tubular metal bushings fixed in the links. The hinge forming screws are fixed in the supports 14 or the machine base 18 as the case may be. All parts so far described, except the screws and bushings, are of wood.

The axes of the hinge connections 22 and 24 are horizontally spaced a distance which is less than the effective length of the links. All of the links are of the same effective length; i. e. the distances between the two hinging axes are the same for all four links. The hinge connections 24 and 25 are lower than the hinge connections 22 and 23 by an amount such that when the links swing to horizontal positions, the links on each side of the platform engage. This is clearly illustrated in Fig. 3. A simple way of ensuring this is to make the width of all the links the same and to offset the hinge connections 24 and 25 downward an amount equal to this width.

Variations in form or dimension of the links may be resorted to to ensure collision at the desired point. The important thing is formation of the links so that, in the position of Figs. 2 and 3, they inter-engage. Then the rear links become in effect rigid extensions of the platform, and act to prevent tilting of the forward end of the platform downward.

In the projecting position, shown in Figs. 2 and 3, the platform is sustained on the struts 15 by a latch bar 26 which extends across the lower side of the platform 18 and is slidable transversely (but lengthwise of the platform) in the wooden guides 27. The bar 26 is so located that in its normal position (the full line position of Fig. 5) it will lie above the struts 15 if the platform is in the position of Figs. 2 and 3. It can be forced back far enough to clear the struts and thus permit raising and lowering of the platform.

When the platform hangs by gravity, the links 19 and 21 are vertical and the platform is in an intermediate position between those shown in Figs. 1 and 2. The latching bar 26 is urged to its full line position of Fig. 5 by means of the bow springs 28.

A slidable wooden latch 29 is mounted in the guide 31 near the rear of the lower face of the platform 18 and in its rearward position will engage the upper surface of the cross member 17 to retain the parts in the position of Fig. 1. The latch 29 is fixed to a wooden pull rod 32 which extends to a point near the forward edge of the platform 18 and is confined in a guide 33. A finger piece 34 is attached to the forward end of the pull rod.

Pull rod 32 carries a cross member 35 which actuates a pair of wooden levers 36. These levers are pivoted at mid-length on screws 37 and at their other ends engage the bar 26. Thus when the pull rod 32 is drawn forward, the latch 29 is moved in a releasing direction and at the same time the bar 26 is moved in a releasing direction. The springs 28, which react upon the bar 26, serve also to actuate the latch 29 through the mechanical interaction of these parts.

Assuming that the platform is in the retracted position of Fig. 1 and that the door 12 has been opened, the operator places her hand against the forward edge of the platform 18 and draws the finger piece 34 forward. This releases the latch 29 and the platform will swing by gravity part-way out of the cabinet. It may then be drawn forward and upward. As it approaches the position of Fig. 2, the latch bar 26 will be struck back by collision with the sides of the struts 15 and then will snap forward over the upper ends of the struts 15. This causes the cross bar 26 to become a primary support for the platform. Tilting of the platform will be prevented because the links 19 and 21 at the two sides of the platform are in interengagement as shown in Fig. 3.

When it is desired to return the platform to its housed position, the operator grasps the forward end of the platform, draws the finger piece 34 forward, and lowers the machine into the cabinet. If she wishes, she can swing it continuously to the retracted position of Fig. 1. If she does so, the latch 29 will be struck back and then engage the upper margin of the strip 17 which acts as a keeper for the latch.

The invention produces a very simple mechanism which can be constructed almost solely of wood and which is sufficiently rugged to stand the abuse ordinarily encountered by a device of this character. The fact that the platform and the machine carried thereby swing naturally to an intermediate position makes it unnecessary to provide counter-balancing springs.

The only metal required in the construction of the device is the small amount necessary for the screws and bushings and the wire bow springs.

The embodiment above described in detail is 75

intended to be illustrative and not limiting, the scope of the invention being defined solely in the claims.

What is claimed is:

5. The combination of a cabinet; supporting means carried by the cabinet; a horizontal machine platform movable between a projecting position and a retracted position; four substantially identical links hinged on parallel axes at their upper ends to said supporting means and at their lower ends to the platform, said links being arranged in parallel pairs, the links of each pair being spaced a distance less than the effective length of the links and arranged to 10 swing in a common plane, one link of each pair being hinged sufficiently lower than the other to cause the two links in each pair to engage when the platform reaches its projecting position and substantially as the links reach 15 horizontal positions, and means for latching said platform in its projecting position to the supporting means at a point forward of the inter-engagement of the links.

25. The combination of a cabinet; supporting means carried by the cabinet; a horizontal machine platform movable between a projecting position and a retracted position; four substantially identical links hinged on parallel axes at their upper ends to said supporting means and 30 at their lower ends to the platform, said links being arranged in parallel pairs, the links of each pair being spaced a distance less than the effective length of the links and arranged to swing in a common plane, one link of each pair being hinged sufficiently lower than the other to cause the two links in each pair to engage when the platform reaches its projecting position and substantially as the links reach horizontal positions; a shiftable latching bar extending across the lower face of the platform; and means associated with said supporting means and adapted to be engaged by said bar and then to support the bar when the platform is in its projecting position.

40. The combination of a cabinet; supporting means carried by the cabinet; a horizontal machine platform movable between a projecting position and a retracted position; four substantially identical links hinged on parallel axes at their upper ends to said supporting means and at their lower ends to the platform, said links being arranged in parallel pairs so located that under the action of gravity the platform seeks a position intermediate its projecting and retracted positions, the links of each pair being spaced a distance less than the effective length of the links and arranged to swing in a common plane, one link of each pair being hinged sufficiently lower than the other to cause the two links in each pair to engage when the platform reaches its projecting position and substantially as the links reach horizontal positions; means for latching said platform in its projecting position to the supporting means at a point forward of the inter-engagement of the links; means for latching said platform in its retracted position; and a single means for actuating said latching means.

45. The combination of a cabinet; supporting means carried by the cabinet; a horizontal machine platform movable between a projecting position and a retracted position; four substantially identical links hinged on parallel axes at their upper ends to said supporting means and at their lower ends to the platform, said links

being arranged in parallel pairs so located that under the action of gravity the platform seeks a position intermediate its projecting and retracted positions, the links of each pair being spaced a distance less than the effective length of the links and arranged to swing in a common plane, one link of each pair being hinged sufficiently lower than the other to cause the two links in each pair to engage when the platform reaches its projecting position and sub-

stantially as the links reach horizontal positions; means for latching said platform in its projecting position to the supporting means at a point forward of the inter-engagement of the links; means for latching said platform in its retracted position; a spring serving to bias both said latching means in an engaging direction; and a single latch controller operable to move both said latches in a releasing direction.
